UNITED STATES PATENT OFFICE.

SAMUEL LEWIS VAN AKIN, JR., OF LACKAWAXEN, PENNSYLVANIA.

PENHOLDER.

SPECIFICATION forming part of Letters Patent No. 650,880, dated June 5, 1900.

Application filed November 23, 1899. Serial No. 737,999. (No model.)

To all whom it may concern:

Be it known that I, SAMUEL LEWIS VAN AKIN, Jr., a citizen of the United States, residing at Lackawaxen, in the county of Pike and State of Pennsylvania, have invented certain new and useful Improvements in Penholders, of which the following is a full and complete specification, such as will enable those skilled in the art to which it appertains to make and use the same.

This invention relates to penholders, and has for its object to provide a simple, cheap, readily-constructed, and perfectly-operating device, by means of which the operative end 15 of the penholder may be adjusted laterally at either side to cause the pen to lie at any desired angle to the main body or shank of the penholder, according to the requirements of the writer.

20 My invention consists in the novel construction and arrangement of parts herein-after fully described.

In the accompanying drawings, forming a part of this specification, in which like letters 25 of reference denote corresponding parts in the several views, Figure 1 is a longitudinal central section of a penholder embodying my invention, the shank being in elevation. Fig. 2 is a plan view of the same. Fig. 3 is a side 30 elevation of the device, partly in section; and Figs. 4 and 5, respectively, side and plan views of a portion of the penholder, showing several details of construction.

In the practice of my invention I form the 35 shank A of the penholder of wood or any other suitable material, upon the lower end whereof I secure a preferably metallic tube B, secured in any desired manner. Within this tube B is inserted a small sliding cylinder a, the forward end of which is closed and provided with a plurality of teeth b. Behind the short cylinder a is a spiral spring C, the tendency of which is to expand, and one end of which projects into the cylinder a to force the same forwardly or outwardly, such movement of the 40 cylinder being limited by a small integral stud c, formed upon said cylinder and working in a longitudinal slot d in the tube B.

Upon the tube B are formed two upwardly 45 ranging and slightly inwardly deflected lugs e. In these lugs is pivoted a short supplemental tube D, which is provided with the

split metallic block E, whereby to hold a pen frictionally, as ordinarily with penholders of the present type. The rear or inner edge of 55 the tube D is in both the upper and the lower faces thereof provided with slots f at either side of the lugs e of the tube B, between which slots are accordingly formed lugs g, engaging the outer faces of the lugs e, and through 60 these lugs g and e is inserted a pin h, which serves as a journal or spindle for the tube D; whereby the same is laterally movable to either side relatively of the tube B, the lugs g being on the outside of the lugs e. 65

Formed integrally with the rear or inner edge of the tube D is a segmental rack i, the teeth j of which in practice mesh with the teeth b of the cylinder a. Over the whole forward or finger portion of the penholder, 70 comprised by the two tubes B and D, I place a sheath or tubular cover F, of rubber or similar flexible and, preferably, elastic material, which is open at both ends.

The operation of the device will be readily 75 understood from the foregoing description when taken in connection with the accompanying drawings. A pen being placed in the holder and it being desired to write, the stud c is pressed rearwardly by the finger to withdraw the teeth b of the cylinder a from engagement with the teeth j upon the tube D, and the said tube D is turned either to the right or the left, as the writer may desire, according to his customary position or angle 80 85 relatively to the writing-surface, or according to his customary manner of holding the pen, or according, furthermore, to whether he writes with the right or the left hand. In this movement of the tube D the lugs e of 90 the tube B will enter the slots f, and the limit of movement of the said tube D will be governed by the depth of said slots relatively to the width of the lugs e. The tube D having been adjusted to the desired angle, the 95 stud c is released, thereby permitting the cylinder a to be forced by the spring C forwardly or outwardly, whereby the teeth b thereof engage the teeth j of the segmental rack i, thus holding the said tube D in its adjusted angular position. The rubber sheath 100 serves to cover up the joints of the two parts and to keep ink or dust from getting in the same to clog them, and by reason of the par-

ticular arrangement of the parts, whereby the tube D is outside of the lugs e, the whole device presents an even and comparatively-smooth surface to the fingers of the writer.

5 Having fully described my invention, I claim as new and desire to secure by Letters Patent—

1. A penholder having a movable pen-receiving end pivoted thereto and adapted to swing laterally, and spring-projected means within the penholder for engaging said movable end to hold the same in any adjusted position; the said engaging means being adapted to be temporarily released to permit adjustment of said movable end.

15 2. A penholder having a movable pen-receiving end connected therewith, whereby it swings laterally, and which is provided with a serrated surface within its point of connection with said penholder; and spring-actuated means upon the penholder for engaging said serrated surface, and adapted to be temporarily released therefrom.

25 3. A penholder having a movable pen-receiving end connected therewith and adapted to swing laterally to either side thereof; a locking device mounted within the penholder and provided with means for engaging the movable end to retain it in the adjusted position; and a rubber sheath surrounding the penholder and the movable end.

35 4. A penholder having a movable pen-receiving end connected therewith and adapted to swing laterally to either side thereof; a locking device mounted within the penholder and provided with means for engaging the movable end to retain it in the adjusted position; a flexible sheath surrounding the penholder and the movable end; and releasing 40 means connected with the locking device within the penholder and projecting through the outer sheath.

5. A penholder having a movable pen-receiving end pivoted thereto and adapted to swing to either side thereof, and provided with a segmental serrated cross-bar within its pivotal point of connection with the penholder; a sliding cylinder mounted within the penholder and provided with a serrated face adapted to engage the segmental bar to lock the movable end in its desired adjustment; a spring within the penholder bearing against the sliding cylinder to normally project the same, and a stud upon said cylinder projecting through the wall of the penholder; said penholder being slotted to receive said stud therethrough.

50 6. A penholder having a tube secured to one end thereof which is provided with upwardly-projecting, inwardly-deflected lugs, said penholder being slotted; a pen-receiving tube mounted over and upon said lugs and slotted at either side thereof and pivoted thereto by a spindle passing therethrough; said tube having an integral segmental rack 55 provided with teeth; a short hollow cylinder sliding in the penholder and provided with teeth to engage the teeth of the segmental rack; a spring within the penholder and entering the sliding cylinder to normally project the same; a stud mounted upon the said cylinder and extending through the slot in the penholder; and a rubber sheath mounted upon and incasing the operative end of the penholder and slotted to receive the said stud therethrough.

70 In testimony that I claim the foregoing as my invention I have signed my name, in presence of the subscribing witnesses, this 13th day of November, 1899.
